AIR COMPRESSING APPARATUS

Fredrick Alfred Edward Jenkins, Canterbury,
near Sydney, New South Wales, AustraliaApplication October 20, 1932, Serial No. 638,785
In Australia July 14, 1932

15 Claims. (Cl. 230—56)

The general object of this invention is to provide compact self-contained and economical apparatus for compressing air for any purpose to which compressed air may be usefully applied.

A further object is to provide apparatus which will automatically restart the compressor unit should the latter have stopped and the pressure in the receiving vessel be reduced below a set minimum.

Apparatus according to this invention includes a main reservoir for compressed air, and a smaller reservoir for air at a much higher pressure and used as a starting medium, this smaller reservoir being hereinafter referred to as the starting reservoir; it also includes a crankless, two-cycle, double-acting main compressor unit of novel design operating on the Diesel principle and having opposed power cylinders and one air compressing cylinder fitted with a reciprocating piston, said compressor unit being further characterized in that air compressed in the compressing cylinder is passed through the firing or power cylinders to, first, scavenge the latter and carry the gaseous products of combustion with it into the main reservoir thus storing them under pressure with the air, and, secondly, to provide in each power cylinder a charge of air to be further compressed on the outward stroke of each power piston sufficiently to raise its temperature to that required to effect combustion when the charge of oil fuel is admitted.

The apparatus also includes means, operated manually, electrically or otherwise, for initially charging the starting reservoir to the required pressure when there is no pressure or insufficient pressure in the main reservoir. Other automatic means are provided for maintaining the required pressure in the starting reservoir when there is pressure in the main reservoir, the last mentioned automatic means, which consists of an air-driven pump, being controlled by the pressure in the starting reservoir and actuated by air from the main reservoir.

The apparatus also includes a pair of selector valves whereby air from the charged starting reservoir is admitted to either one of the power cylinders selectively for initially starting the main compressor unit, this operation being manually controlled by a master valve, and also to restart said unit should it have stopped as a result of the resistance offered by accumulated pressure to a predetermined value in the main reservoir, or for other reason, the restarting being automatically effected by operation of the master valve per medium of an automatic control device,

on reduction of pressure in the main reservoir as the result of utilization of air therefrom after the compressor unit has ceased to operate. It will be observed that the initial starting and re-starting is dependent upon the existence of sufficient air pressure in the starting reservoir.

Associated with the compressor unit is an arrangement of cams and tappets whereby the beforementioned pair of selector valves are actuated alternately at each stroke of the compressor, though the connection to the starting reservoir is not made unless the master valve is opened; another pair of tappets, actuated by the same cam device, operate respectively an oil-fuel pump and a lubricating oil pump.

The last mentioned tappets are optional, as the supply of oil-fuel and lubricating oil under pressure may be provided by other means.

For compactness, the starting reservoir together with passages therefrom to the inlets of the power cylinders, is preferably built into the structure of the main reservoir which serves as a base or foundation for the compressor unit; this arrangement is however not essential.

The foregoing and other features of the invention are fully and completely ascertained by the following description of the accompanying drawings which depict a practical embodiment of the invention and in which

Fig. 1 is a schematic perspective view of the complete apparatus;

Fig. 2 is a longitudinal sectional elevation;

Fig. 3 is a sectional plan on line III, III of

Fig. 2,

Fig. 4 is a part cross sectional elevation on line IV, IV, of Fig. 2;

Fig. 5 is a part cross sectional elevation on (approximately) line V, V of Fig. 2;

Fig. 6 is a part cross sectional elevation on line VI, VI, of Fig. 2;

Fig. 7 is a part cross sectional elevation on plane VII, VII of Fig. 1, showing the master valve and its associated control device for automatic re-starting;

Fig. 8 is a part cross sectional elevation on plane VIII, VIII of Fig. 1 showing details of the automatic control for starting the air pump to recharge or maintain the pressure in the starting reservoir;

Fig. 9 is a longitudinal sectional elevation of the air-compressing cylinder taken on line IX, IX, of Fig. 5;

Fig. 10 is a sectional plane (to a larger scale) of the head of one of the power cylinders and the piston head in said cylinder, showing clearly

the arrangement of valves and passages in these parts;

Fig. 11 is a sectional elevation of portion of the reservoir structure, taken on line XI, XI of Fig. 3.

The main parts of the compressor unit comprise a central air-compressing cylinder 12 and two power cylinders 13 and 13' attached respectively to the heads 12' and 12'' of the air compressing cylinder, the outer ends of these power cylinders having heads 14 and 14' respectively which constitute valve boxes and are formed on the upper ends of tubular standards 15 and 15'. These standards support the unit on a hollow structure which constitutes the main reservoir 17 for compressed air, and in the upper part of which is constructed the starting reservoir 18 of substantially triangular form as clearly shown by dotted lines in Figs. 1 and 3. This starting reservoir is comparatively shallow and of relatively small capacity.

Externally of the reservoir structure is an electrically operated air pump 20 for supplying air through pipe 21 to the starting reservoir and establishing the required initial air pressure therein, this pressure being utilized in initially starting and in automatically re-starting the compressor unit.

There is also provided an air-driven pump 22 for automatically supplying air to the starting reservoir and maintaining the pressure therein; this air pump is driven by air from the main reservoir 17 through pipe 23 and discharges to the starting reservoir through pipe 24.

The details of the compressor unit are most clearly shown in Figs. 2 and 3. A hollow reciprocating piston element common to the air compressing cylinder 12 and both power cylinders, is formed in two parts 26 and 26' fitted respectively to opposite sides of piston 29 in the cylinder 12 and at their outer ends formed with hollow plunger-heads 27, 27' respectively, these heads fitting in the power cylinders. In these heads 27 and 27' respectively are spring-loaded valves 28 and 28' opening outwardly. Near the outer end of each part of the piston element is a transverse partition 13''.

Both parts of the piston element are formed with double walls providing between them annular spaces 30 and 30' respectively which communicate at their outer ends through ports 31 and 31' with the hollow heads 27 and 27', and at their inner ends, through passages 32 and 32' formed in the piston 29 (Figs. 2 and 4), with opposite ends respectively of the air compressing cylinder 12 irrespective of the position of the piston 29 at any time.

Fitting about the parts 26, 26' and forming part of the hub of piston 29 is a double-ended cam sleeve 34 with bevelled ends which, as the piston 29 is reciprocated, enter annular recesses 35, 35' in the ends respectively of the cylinder 12. This cam operates tappet gear by means of which valve mechanism is actuated as herein-after explained, and also operates other tappet gear actuating fuel oil and lubricating oil pumps.

In the heads 12', 12'' of cylinder 12 are a series of automatic spring-loaded air-admission valves 36 (see Figs. 5 and 9).

In the head or valve box 14' of power cylinder 13' are two valves 37' and 38'; valve 37' is a spring-loaded and timed air-discharge valve which when opened inwardly as herein-after explained, establishes communication between power cylinder 13', through passage 39' in standard 15', and the

main reservoir 17; valve 38' (Fig. 3) is a spring-loaded valve opening inwardly and normally closing communication between the starting reservoir 18, through passage 40' in standard 15', and the cylinder 13'. Also in the head 14' is a spring-loaded needle valve 41' controlling the admission of fuel-oil from pipe 42 (see Fig. 6). In the other head 14 is a similar group of valves indicated respectively by numerals 37, 38 and 41, and in the standard 15 are similar passages 39 and 40 respectively (see Fig. 10).

The mechanism actuating valves 37, 41 and 37', 41' is most clearly shown in Fig. 2. In this figure, the piston 29 is shown in its extreme position at the left-hand end of cylinder 12, and cam 34 having entered recess 35, tappet 44 is lifted thereby and actuates crank-lever 45 pivoted at 46 to a bracket 47 mounted on a bridge bar 48 secured to cylinder 12. To the upper end of crank-lever 45 there are pivotally connected two rods 49 and 50, rod 49 being adjustably connected at its other end to crank-lever 51 which engages the stem of oil-fuel needle valve 41, while rod 50 at its other end is connected to one end of pivoted lever 52' the other end of which bears upon the stem of valve 37'. At the other end of cylinder 12, tappet 44' is in engagement with crank lever 45', this lever being connected to rods 49' and 50' which are similarly connected respectively to crank lever 51' actuating needle valve 41', and to lever 52 actuating the air discharge valve 37. It will thus be seen that when the piston 29 and piston head 27 are at or near the left hand ends of their cylinders respectively, oil-fuel valve 41 at the left, and air discharge valve 37' at the right, are opened, but these valves close as those pistons move towards the right, and that when piston 29 and piston head 27' are at or near the right hand ends of their respective cylinders, oil-fuel valve 41' and air discharge valve 37 are opened.

Disposed at right angles to the tappets 44, 44' are other tappets 54, 54' and 55, 55' arranged in pairs at opposite ends of cylinder 12 (see Figs. 3 and 5); these tappets are actuated by the cam 34. Tappets 54, 54' operate oil-fuel pumps 56 of known type to supply oil-fuel under pressure to a receiver (not shown) whence it is conveyed to the oil-fuel valves 41, 41'. Tappets 55, 55' operate pumps 57 for supplying lubricating oil under pressure. These tappets 54, 54' and 55, 55' are returned by springs 59.

Disposed oppositely to tappets 44, 44' respectively are two more tappets 60, 60' also actuated alternately by cam 34, their outer ends bearing upon rocker arms 61 each of which is pivoted at one end on a bracket 62 (Fig. 5) and at its other end, in which is an adjusting screw 63, bears upon one end of a bar 64 centrally pivoted at 65. As the cam 34 reciprocates, the tappets 60, 60' effect an oscillation of bar 64 about its pivotal point 65, and as the bar oscillates, the selector valves 66, 66' upon the stems of which bear respectively opposite ends of the bar 64, are alternately opened for a purpose herein-after explained. In Fig. 2, tappet 60 is shown as depressed by cam 34, and the left hand end of bar 64 in which is a notch 67 is engaged by a spring detent 68. In this position of the parts the selector valve 66 is open as shown, its spring 69 being compressed, and valve 66' is closed, the closure being effected by spring 69'. This disposition will remain until the cam 34 has moved sufficiently to the right to release tappet 60 and engage tappet 60' and thus depress the other end of bar 64, thereby

80

opening valve 66', the other valve 66 automatically closing. In this position the spring detent 68' engages the notch 67'.

5 Springs 69, 69' serve no other purpose than to seat the valves 66, 66' and therefore may be of light construction so that the spring detents 68, 68' are required to do no more than hold the bar in set position (one end depressed) until this position is reversed by movement of cam 34. The 10 retention of one admission valve in open position during this period is essential as will be explained later.

The position of these selector valves 66, 66' is shown by dotted circles in Fig. 3 and their function 15 is to selectively control the flow of high pressure air from passages 70, 70' which communicate with the starting reservoir 18 through a master valve or control valve 71, to passages 72, 72' respectively which in turn communicate with 20 port passages 40, 40' in standards 15, 15' and so through valves 38, 38' to the power cylinders. This arrangement of passages is most clearly shown in Fig. 11 which depicts in sectional elevation the passages and valves to the right of the 25 master valve.

The master valve 71 and its regulating means indicated generally by numeral 73, are clearly shown in Fig. 7. The valve which is spring-urged to its seat, controls communication between the 30 starting reservoir 18 and passage 70, and is opened by depression of lever 74 pivoted at one end on a bracket 75. Depression of the lever may be effected both manually and automatically. The free end of the lever is connected by a flexible 35 cord 76 to a stem 77 of a plate 78 fitted to a flexible diaphragm 79 which is subjected on its underside to the pressure existing at any time in the main reservoir 17 and urged against said pressure by a spring 80. While the pressure in 40 the main reservoir is sufficient to counteract that of the spring 80, the lever 74 and valve 71 are unaffected and the valve is normally closed. Should however the pressure in the main reservoir fall to the extent that the spring pressure on the 45 diaphragm is the greater, then the lever 74 is drawn downwardly, the valve 71 is opened, and communication is established between the starting reservoir 18 and passage 70.

The automatic means for control of the air-driven pump 22 is shown clearly in Fig. 8. An air chamber 82 is constructed in the main reservoir (see also Figs. 1, 2 and 3) and from it the pipe 23 leads to the pump 22. Chamber 82 is in communication with the main reservoir through 50 a spring-loaded valve 83 which is opened by depression of lever 84 pivoted at one end to bracket 85. The other end of lever 84 is coupled to and actuated by a control device indicated generally by numeral 86 similar to the control device shown 55 in and described in reference to Fig. 7, but so located that its diaphragm is subject to the pressure in the starting reservoir 18. Should this pressure fall below a set minimum the valve 83 is automatically opened and air from chamber 82 is supplied to start the air-driven pump 22 for the purpose of re-establishing the required pressure in the starting reservoir. Obviously the operation of pump 22 depends on the existence of sufficient pressure in the main reservoir. Otherwise the starting reservoir may be charged by 60 means of pump 20.

The operation of the apparatus will now be described, it being understood that a condition precedent to starting is the establishment of high air pressure in the starting reservoir and a sup-

ply of oil fuel under pressure. Further, it will be assumed that the parts are in the relative positions shown in Fig. 2 with the exception that valve 28' in piston head 27' is closed instead of open as shown, this closure being the natural effect of the valve spring. 80

To start the compressor unit, the master valve 71 is opened by manual depression of lever 74, and air from the starting reservoir 18 enters passage 70, and thence passes through selector valve 66, passages 72 and 40 (Fig. 10) and valve 38 (which is opened by the air pressure) into power cylinder 13. The effect of this air pressure is to drive the piston assembly to the right, some of the air in power cylinder 13' being discharged through valve 37' into the main reservoir 17. When cam 34 leaves tappet 44 valve 37' closes and the remaining air in cylinder 13' is compressed. 85 90

Meantime, air is compressed in cylinder 12 by the movement of piston 29, this pressure being communicated through passages 32, annular passage 39 and ports 31 to the hollow piston head 27, but owing to excess pressure on the outside of valve 28 it cannot escape therethrough until 95 cam 34 actuates tappet 44' to open valve 37, when the excess pressure is released and passes, together with the air from cylinder 12, which now opens valve 28, through valve 37 and passage 39 to the main reservoir 17. 100 105

The contact of cam 34 with tappet 44' results in opening of the oil-fuel valve 41', and if the imprisoned air in cylinder 13' is, as a result of compression after closure of valve 37', raised to a sufficiently high temperature, the oil-fuel charge 110 from valve 41' will be fired and as a result of combustion the piston assembly will be propelled in reverse direction, thus compressing air in cylinder 12 between head 12' and piston 29. Should the required pressure and temperature to effect 115 combustion of the oil-fuel charge, not be obtained on the first stroke, the master valve is held open and, the positions of valves 66, 66' being reversed as the result of cam 34 actuating tappet 60', air from the starting reservoir 17 flows through valve 66' passages 72', 40' and 120 valve 38' to cylinder 13' thus effecting a return stroke of the piston assembly, allowing valve 37 to close and compressing air in cylinder 13. This compression is greater than on the first 125 stroke owing to the fact that some initial pressure exists in cylinder 13 as a result of the first stroke. 130

This reciprocation of the piston assembly by air from the starting reservoir is continued as 135 required until sufficient pressure and temperature is obtained in one power cylinder to effect the required combustion of the oil-fuel charge, whereupon the master valve 71 is permitted to close and the compressor unit takes up normal 140 running, a charge being fired in each power cylinder alternately. 145

Assuming that a charge has been fired in cylinder 13' and the piston assembly is in the position shown in Fig. 2, valve 37' being opened by the action of cam 34 on tappet 44; the pressure in cylinder 13' is equal to that in the main reservoir 17, and air compressed in cylinder 12 between head 12' and piston 29, passes by way of passages 32', annular passage 30', ports 31' and hollow piston head 27' through valve 28' into cylinder 13', and through valve 37' into the main reservoir 17. Thus the products of combustion are scavenged from cylinder 13' and carried into the main reservoir before valve 37' is closed on the 150

return stroke and compression in cylinder 13' again commences.

Similarly, if a charge is fired in cylinder 13 and the piston assembly moved to the right, air compressed in the other end of cylinder 12 passes by way of passages 32 and 30, ports 31, and valve 28 into cylinder 13, and thence through the now open valve 37 into reservoir 17.

The automatic re-starting of the compressor unit, should the pressure in the main reservoir fall below a set minimum, is effected in a similar manner to the initial starting, except that the opening and closing of the master valve is automatically controlled by the air pressure in the main reservoir acting on the control device 73. An air take-off for the reservoir 17 is indicated at 88 in Figure 1.

What I claim and desire to secure by Letters Patent is:

20. 1. A crankless direct acting air compressor operating on the Diesel principle, comprising an air compressing cylinder, opposed power cylinders extending from opposite ends of the compressing cylinder and in axial alignment therewith, said air compressing cylinder having automatic air admission valves; a reciprocating element common to all three cylinders and comprising a piston in the compressing cylinder and plungers extending in opposite directions therefrom and operating in the said power cylinders, said piston having air ducts leading from opposite sides of the compression cylinder and said plungers having air ducts leading from those of the piston, an outwardly opening valve at the outer end of each plunger and to which one of said ducts leads, so that air compressed between the piston and each head of the compressing cylinder is delivered into the power cylinders to scavenge the latter, and compressed air discharge ducts and valves at the outer ends of the power cylinders.

25. 2. An air compressor as claimed in claim 1, including oil fuel admission valves at the outer ends of the power cylinders and means actuated by the reciprocating piston element to operate said valves.

30. 3. An air compressor as claimed in claim 1, including means actuated by the reciprocating piston element to operate said valves for admitting air at high pressure into the power cylinders selectively for starting purposes.

35. 4. An air compressor as claimed in claim 1, in which each plunger is hollow and together with the piston is provided with a duct leading from one side of the piston to a point near the outer end of the plunger extending from the opposite side of the piston and in which each plunger is hollow and is provided at the outer end with a spring loaded outwardly opening valve.

40. 5. An air compressor as claimed in claim 1, including discharge valves and oil-fuel valves, springs for closing said valves, and means for operating them comprising two sets of cam and tappet gears each set controlling the discharge valve at the end of one power cylinder and the oil-fuel valve at the end of the other power cylinder.

45. 6. An air compressor as claimed in claim 1, including discharge valves and oil fuel valves, springs for closing said valves and means for actuating said valves, comprising a sleeve cam on the piston element, a pair of tappets located respectively at the ends of the air compressing cylinder and actuated alternately by said cam, and link and lever mechanism whereby the move-

ment of each tappet opens a discharge valve at the end of one power cylinder and an oil-fuel valve at the end of the other power cylinder.

50. 7. An air compressor as claimed in claim 1, including means for admitting starting air to the power cylinders, said means comprising compressed air supplying means, ducts connecting said supplying means with the power cylinders respectively, a selector valve in each such duct, and means actuated by reciprocation of the piston element for opening said valves alternately. 80

55. 8. An air compressor as claimed in claim 1, including means for admitting starting air to the power cylinders selectively, said means comprising compressed air supplying ducts, means connecting the power cylinders respectively with said supplying means, an automatic valve in each such duct opening directly into one of the power cylinders, a pair of selector valves located one in each such duct and tappet mechanism, and means to operate such tappet mechanism actuated by reciprocation of the piston element, and a master valve controlling the supply of high pressure air to said selector valves. 90

60. 9. An air compressor as claimed in claim 1, including means for supplying starting air to the power cylinders respectively, said means comprising compressed air supplying means, ducts connecting said supplying means with the power cylinders, a pair of selector valves located in such ducts and having stems, a centrally pivoted bar bearing at its ends respectively on the stems of said valves and tappet mechanism actuated by reciprocating movement of the piston element to oscillate said bar and cause the same to open 100 said valves alternately, a master-valve controlling the supply of compressed air to said selector valves, and detent means for holding an opened selector valve in open position until the other is about to be opened. 110

65. 10. An air compressor as claimed in claim 1, including an air reservoir means for supplying said air reservoir with compressed air, a pair of spring-closed selector valves controlling the supply of compressed air from said reservoir to the power cylinders selectively for starting purposes, means whereby said selector valves are opened alternately by reciprocation of the piston element, a master valve controlling the supply of air to said selector valves, a compressor for charging such reservoir, a master valve, means for automatically effecting the opening of the said master valve and thus restarting the compressor should it have stopped and the pressure in said air reservoir have fallen below a set minimum, said means comprising a movable element coupled to the master valve, subjected on one side to the pressure in said reservoir and a spring exerting sufficient force on the other side of said movable element to overcome a fluid pressure below the set minimum and under such condition to move said element in a direction to open the valve. 120

70. 11. An air compressor as claimed in claim 1, including an air reservoir, means to charge the same with compressed air, a pair of selector valves controlling the supply of compressed air by said reservoir to the power cylinders for starting purposes, a master valve controlling the supply of starting air to said selector valves, a lever to actuate the same, an automatic device for opening the master valve on reduction of pressure in the air reservoir below a set minimum, and a flexible connection between the lever of the master valve and the automatic device to enable 130

said valve to be opened manually and automatically.

reservoir and the power cylinders, selector valves in said ducts, a cam on the piston, tappets actuated by said cam for opening said selector valves alternately, and a master valve for controlling the supply of air from the starting reservoir to said ducts. 80

12. Air compressing apparatus, as claimed, in
claim 1 including an air compressor, a main
5 air reservoir into which the compressor delivers
compressed air, a second reservoir to contain a
supply of air at high pressure for starting pur-
poses, means for initially charging the second
reservoir, and means for supplying air to main-
10 tain the required pressure in the second reservoir,
and means whereby the last mentioned means is
automatically controlled by the pressure in the
second reservoir, said means being actuated by
air from the main reservoir.

14. An air compressor as claimed in claim 1,

15 13. Air compressing apparatus including a main reservoir for compressed air, a second starting reservoir incorporated therewith to contain a supply of compressed air for starting purposes, means for initially charging the second 20 reservoir, an air compressor unit comprising a central air compressing cylinder, a piston therein, air inlet valves at each end of said cylinder, two power cylinders attached to the opposite ends of the compressing cylinder, plungers attached 25 to opposite sides of said piston and having hollow heads fitting the power cylinders, a spring loaded valve opening outwardly in each such hollow plunger head, ducts establishing communication respectively between the interior of 30 each plunger head and the remote end of the compressing cylinder, a valve box at the outer end of each power cylinder having two passages opening into the power cylinder, one being a discharge passage communicating with the main 35 reservoir and the other an air inlet passage in communication with the starting reservoir, spring-loaded discharge and air inlet valves opening inwardly into the power cylinder at the ends of these passages respectively, an oil-fuel admission valve in said valve box, a tappet at each 40 end of the compressing cylinder, a cam on the piston to actuate said tappets, link and lever mechanism actuated by the tappets, an oil-fuel valve at the end of one power cylinder and a 45 discharge valve at the end of the other, actuated by said link and lever mechanism, to open the other pair of these valves as the piston assembly reciprocates, ducts connecting the starting

including an air reservoir, means to charge the same with compressed air, a pair of selector valves controlling the supply of compressed air by said reservoir to the power cylinders for starting purposes, a master valve controlling the supply of starting air to said selector valves, a lever to actuate the same, an automatic device for opening the master valve on reduction of pressure in the air reservoir below a set minimum, and a flexible connection between the lever of the master valve and the automatic device to enable said valve to be opened manually and automatically and means controlled by the pressure in the reservoir for automatically opening the master valve on reduction of said pressure below a set minimum.

15. An air compressor as claimed in claim 1, including an air reservoir, means to charge the same with compressed air, a pair of selector valves controlling the supply of compressed air by said reservoir to the power cylinders for starting purposes, a master valve controlling the supply of starting air to said selector valves, a lever to actuate the same, an automatic device for opening the master valve on reduction of pressure in the air reservoir below a set minimum, and a flexible connection between the lever of the master valve and the automatic device to enable said valve to be opened manually and automatically, a main reservoir, a starting reservoir, an air chamber in valved communication with the main reservoir, an air driven pump supplying air at high pressure to the starting reservoir, and an automatic device subjected to the pressure in the starting reservoir and operating on reduction of pressure in the latter to open the communication valve and set the air pump in operation to reestablish the pressure in the starting reservoir. 120
